LIPSTICK HOLDER

Simon Morrison, New York, N. Y.

Application July 29, 1931, Serial No. 553,719

12 Claims. (Cl. 206—56)

This invention relates to containers and particularly to those adapted to hold lipstick or other similar cosmetics.

Devices of this nature are usually carried in ladies' handbags, where they are frequently subject to careless usage. Removable or poorly fitting covers easily become lost or separated from the containers, and the contents are exposed to contamination. Lipstick and pomade, thus unprotected, cause damage by discoloring articles with which they come in contact.

These disadvantages have been overcome in the present invention, the general object of which is to provide a lipstick holder of dustproof construction having a hinged cover normally held in a positively locked condition.

Another object of the invention is to provide a means for automatically unlocking the device, opening the cover and feeding the contents by a single motion of the thumb-plate.

Further advantages will be evident from the following description and from the accompanying drawings of which

Figure 1 is a side elevational view showing the device in normal closed position.

Figure 2 is a longitudinal section showing the device in closed position, taken on line 2—2 of Fig. 1.

Figure 3 is an enlarged cross-sectional view taken along the line 3—3 of Figure 1.

Figure 4 is an elevational view showing the device in open position.

Figure 5 is a longitudinal section of the device in open position taken on the line 5—5 of Fig. 4.

Figure 6 is an enlarged sectional view taken along the line 6—6 of Fig. 4.

Figure 7 is a side elevational view showing a modified form of the present invention in closed position.

Figure 8 is a longitudinal section taken along the line 8—8 of Figure 7.

Figure 9 is a cross-section taken on the line 9—9 of Figure 10.

Figure 10 is a side elevation of the modified form in open position.

Figure 11 is a longitudinal section taken along the line 11—11 of Figure 10.

Figure 12 is a cross-section taken along the line 12—12 of Figure 7.

Referring now to the drawings, and more particularly to Figures 1 to 6 inclusive, the device, in accordance with the illustrated embodiment, comprises an outer casing 1, a part of which forms in effect a hinged cover 2, which, in closed position, completes the outline of the exterior of

the device. Within the outer casing and its associated covered part, is a longitudinal shell 3 open at either end and provided with a slot 4 extending lengthwise thereof. This inner shell 3 serves as a protective liner for the container and acts as a slideway for a receptacle 5 closed at one end and open at the top, which receptacle holds the crayon 6 of cosmetic or other similar or suitable material. Rigidly connected to the receptacle 5 and riding in the slot 4, is a follower or sliding member 7, to the outside of which is secured in any convenient manner a thumb-plate 8.

Secured to the lower end of the cover member 2 and extending through an opening in the inner shell 3, is a lever member 9 which, in conjunction with the follower 7, serves to lock the cover 2 in closed position. This lever 9, if desired, may be formed as an integral part of the cover 2, as shown clearly in Figures 4 and 5, but other suitable arrangements may be utilized, as will be apparent to those skilled in the art. As shown in the drawings, the cover 2 has one edge thereof cut at an angle, as indicated at 15, the edge of which cut portion serves as a cam against which the follower 7 may press to open the cover, which is of such extent as to substantially completely cover the slot 4 when the device is closed. A portion of the lower part of the inner shell 3 is cut away to form a surface 10, which surface serves as a stop for the lower end of the lever 9 to limit the movement of a cover 2.

The assembly and operation of the device is substantially as follows: The component parts of the container are assembled to cause the receptacle 5 to be mounted within the inner shell or liner 3, and the follower 7, with thumb-plate 8 is secured to the receptacle 5 with the follower extending through slot 4. The receptacle 5 may be then loaded with a pencil 6 of lipstick or other similar cosmetic, and the arrangement is such that upon the pencil being worn away, the old one may be removed and replaced by a new one. When the receptacle 5 is in the bottom of the container, the follower 7 rests in that part of slot 4 below the cover 2 and, due to the contact between the follower and the lever 9, the cover is held locked against movement in any direction. When it is desired to make use of the pencil 6, it is only necessary to slide the receptacle 5 upwardly by pressing against the thumb-plate 8 and moving the same upwardly. This upward movement causes the follower 7 to strike the cammed edge 15 of the cover 2, forcing the cover outwardly and as the follower continues up the slot 4, the cover is moved into the position shown in Figure 4. 55

When the follower has been moved to the top of the slot or any desired distance therealong, the pencil in toto, or any part thereof desired, is exposed for use. Due to the contact of the cam edge 15 with the follower, it is impossible to close the cover so that damage to the pencil is avoided. When use has been made of the pencil and it is desired to close the container, the operation consists of a simple reversal of the hereinbefore described movement, consisting of moving the thumb-plate downwardly, carrying with such movement the follower 7 and receptacle 5. As the follower approaches the bottom of the slot it contacts with the inner edge of lever 9, with the result that upon completion of the downward movement of the thumb-plate the cover 2 is automatically moved into closed position, shown in Figure 1, and held in this position until the thumb-plate and follower are again moved up the slot.

Referring now to the modification shown in Figures 7 to 12 inclusive, the structure is similar in a good many parts to that shown in Figures 1 to 6 inclusive. The device consists of an outer casing 21, a part of which is cut away and hingedly connected to the remainder to form a cover 22 similar to cover 2. Use is also made of an inner shell or liner 23 similar to shell 3, which shell 23 is provided with a longitudinal slot 24. Sliding within the shell 23 is a receptacle 25 for a crayon of cosmetic or other material 26 similar to crayon 6. Secured to the receptacle 25 is a follower 27 to the outer portion of which is fastened in any desired manner a thumb-plate 28. Since both the inner and outer shells or casings are open at each end with the exception of the top of cover 22, a base 32 is provided, which base has a slotted bottom and shell-like sides fitting over the outside of casing 21. The base may be held on the casing 21 by friction or may be soldered thereto or fastened in any other desired fashion. Instead of a locking lever 9, as shown in Figures 1 to 6, inclusive, use is made in this embodiment of a projection 31 formed as an extension of one side of the cover 22. This member 31 cooperates with a surface 34 formed by cutting away a part of the inner shell 23 to limit movement of the cover 2 by contact between the extension 31 and the surface or edge 34. Secured to the extension 31 is a cam member 36, the function of which is to cooperate with the sloping surface of receptacle 25 to force the cover 22 into closed position. As is shown in dotted lines indicated at 35 in Figure 10, one edge of receptacle 25 is sloped instead of being paralleled to its opposite edge, as in the first embodiment of the invention. The cover 22 is hingedly connected, as shown at 33, to the inner shell 23.

Assuming that the parts have been assembled into the position shown in Figure 7 with a crayon 26 fastened in the receptacle 25, the operation of the construction is substantially as follows: The device may open to expose the crayon 26 for use by merely forcing the thumb-plate 28 upwardly, thereby sliding the follower 27 and the receptacle 25 upwardly therewith. After a slight bit of movement, the follower 27 strikes the cam edge of cover 22, swinging the cover 22 about its pivotal axis 33. In this manner the crayon 26 is exposed for use. When it is desired to close the device, the thumb-plate 28 is moved downwardly, drawing the crayon 26 into inner shell 23, and as this downward movement continues, the sloping surface 35 of the receptacle 25 contacts with the cam 36 secured to the extension

31, forcibly moving this extension 31 outwardly and thereby swinging the cover 22 inwardly. Upon completion of the downward movement of the thumb-plate, this movement of cover 22 is sufficient to complete the closing of the container, restoring the parts to the position shown in Figure 1.

From the foregoing it will be seen that the present invention provides an arrangement (in either modification) wherein a lipstick or similar article may be completely enclosed when not in use and may be exposed for use by the simple movement of a single member, which movement may be due to the pressure of a thumb to slide a thumb-plate along the length of the container. The invention also has the advantage that a similar reverse movement completely withdraws the crayon into the interior of the container and simultaneously closes the same so that the crayon is protected from dust or other contamination. In the closed position of the device, the cover is "locked" closed and cannot be opened until the actuator is shifted thereby unlocking the cover for opening. Thus accidental opening of the cover (as during carriage of the holder in a handbag) is minimized. When I say that the cover is "locked" closed, I mean that it will not be opened by forces applied directly to the cover, as by pulling or prying on the cover.

It will be evident from the foregoing that the invention is capable of numerous modifications in view of which it is to be understood that the invention is to be limited not by the illustrated embodiments, but only by the scope of the following claims.

Having described my invention, what I claim is:

1. A container adapted to hold and feed cosmetic material comprising a slotted casing, a sliding member adapted to move in said slotted casing, a hinged cover, and a locking lever attached to said hinged cover and adapted to lock said hinged cover in closed position by pressure of said sliding member against said locking lever.

2. A container adapted to hold and feed cosmetic material and comprising a slotted casing, a sliding member adapted to move in said slotted casing, a hinged cover, and a locking lever attached to said hinged cover and adapted to constrain said hinged cover from moving past a predetermined open position.

3. A lipstick holder comprising an elongated casing having a slot extending longitudinally therein, a sliding member adapted to move along the slot in said casing, a hinged cover normally held in locked closed position, said sliding member being adapted, by a single motion along said slot, to unlock the hinged cover to constrain said hinged cover to move into open position and to prevent said hinged cover from closing.

4. A lipstick holder comprising a casing, a hinged cover, a projection integral with said hinged cover, and a sliding member, said sliding member being adapted to engage said hinged cover and said projection to respectively open and close said cover by cam action.

5. A longitudinal lipstick holder comprising a casing, a hinged cover having a cam edge, a sliding member and a receptacle adapted to hold cosmetic material attached to said sliding member, said sliding member being adapted to move longitudinally to feed said cosmetic material and to simultaneously engage said cam edge of said hinged cover to move said hinged cover into open position.

6. A lipstick holder comprising a casing, a hinged cover, a sliding member, a receptacle attached to said sliding member, a projection attached to said hinged cover and adapted to lock 5 said cover in closed position by engagement with said sliding member, said sliding member being adapted in a single motion to disengage said projection to unlock said cover, to force said cover into open position, and to feed said receptacle.

10 7. A lipstick holder comprising an elongated casing having a slot extending longitudinally therein; a cover hinged to said casing; and a reciprocatory actuator, said actuator being movable along said slot in the casing and being operatively associated with the cover to positively open and close the same; said construction including means to lock the cover in closed position, and said locking means being automatically operated upon movement of the actuator to and 15 from cover-closed position to lock and release the cover respectively.

20 8. A lipstick holder comprising an elongated casing having a slot extending longitudinally therein; a cover hinged to said casing; and a reciprocatory actuator, said actuator being movable along said slot in the casing and being operatively associated with the cover to positively open and close the same; said construction including means to lock the cover in both open and 25 closed position, and said locking means being automatically operated upon movement of the actuator to and from both cover-open and cover-closed position to lock and release the cover respectively.

25 9. A lipstick holder comprising an elongated tubular casing having a slot extending longitudinally therein; a carrier reciprocatable in the casing to project lipstick beyond the casing for use; a cover hinged to said casing; and a reciprocatory actuator, said actuator being movable along 30 said slot in the casing and being connected to the carrier to reciprocate the same and being also operatively associated with the cover to positively open and close the same; said construction in-

cluding means to lock the cover in closed position, and said locking means being automatically operated upon movement of the actuator to and from cover-closed position to lock and release the cover respectively. 5

10 10. A lipstick holder comprising an elongated tubular casing having a slot extending longitudinally therein; a carrier reciprocatable in the casing to project lipstick beyond the casing for use; a cover hinged to said casing; and a reciprocatory actuator, said actuator being movable along 10 said slot in the casing and being connected to the carrier to reciprocate the same and being also operatively associated with the cover to positively open and close the same; said construction including means to lock the cover in both open and closed position, and said locking means being automatically operated upon movement of the actuator to and from both cover-open and cover-closed position to lock and release the cover 15 respectively. 20

25 11. A container of the class described comprising a casing having a longitudinal slot, a carrier slidable in said casing and including an operating portion extending through said slot, a closure pivoted to said casing at a point intermediate the ends of said slot and including an extension below said pivot, said extension lying parallel to said slot when said closure is in closed position, said extension intersecting the path of 30 movement of said carrier when the closure is in open position, whereby said carrier engages said extension during movement of said carrier to retracted position to close and lock said closure.

35 12. A lipstick holder comprising a casing, a hinge cover having an edge including a cam portion and a dwell portion, a carrier movable longitudinally in said casing, a sliding member attached to said carrier to project the same, said sliding member first engaging said cam portion 40 to open said cover and thereafter engaging said dwell portion to hold said cover open.

SIMON MORRISON.
